UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

BAG-FILLING MACHINE.

1,140,867

Specification of Letters Patent. Patented May 25, 1915.

Application filed December 18, 1911. Serial No. 666,599.

To all whom it may concern:

Be it known that I, ADELMER M. BATES, a citizen of the United States, residing at Chicago, in the county of Cook and State of Illinois, have invented a certain new and useful Improvement in Bag-Filling Machines, of which the following is a specification.

My invention relates to improvements in bag filling machines and is illustrated diagrammatically in one form in the accompanying drawings, wherein—

Figure 1 is a part elevation; Fig. 2, a section along the line 2—2 of Fig. 1; Fig. 15 3, a section along the line 3—3 of Fig. 1; Fig. 4, is a rear elevation of the hood removed from the filling machine. Fig. 5, a detailed side elevation. Fig. 6 is a cross section of a modified form of the bag filling 20 machine. Fig. 7 is a front elevation of the bag supporting means.

Like parts are indicated by like letters throughout the several figures.

The feeding spout A discharges into the 25 propeller pocket A¹ in which rotates the usual propeller A² discharging by means of a tangential feeding tube A³ controlled by the shutter A⁴.

The two part cap B formed by the aprons 30 B² and B³ is supported on the feeding tube A³ by the sleeve B¹ which is mounted rigidly upon the apron B². The apron B³ is pivotally mounted at the top on the rod B⁴ which also is pivotally mounted in the apron 35 B². The aprons B², B³ are provided with the overlapping or inwardly bent portions B⁵, B⁶. The overlapping portion B⁶ of the apron B³ is slotted at B⁷ in opposition to the sleeve B¹. The lower edges of the 40 aprons B², B³ are outwardly bent into a substantially horizontal plane as indicated at B⁸, B⁹.

The lug C rigidly mounted on the spron 45 B² carries the rod C¹ pivotally mounted thereon. The lug C² rigidly mounted on the spron B³ furnishes a sliding bearing for the rod C¹. The spiral spring C³ is adapted to be compressed between the lug C² and the nut C⁴ on the rod. The nut C⁴ 50 interposed between the end of the rod C¹ and the lug C² limits the inward travel of the rod through the lug C². The handles C⁵, C⁶ rigidly connected to the sprons B², B³ are adjacent one to the other and fur-

nish a hand hold for the operator whereby 55 the aprons may be rotated one upon the other and operated to release the bag C⁸ which is supported on the horizontally disposed portions of the aprons. The catch C⁹ carried by and rotatable on the handle C⁷, 60 engages the handle C⁶ and is adapted to hold the aprons back against the pressure of the spring until another bag has been placed upon them.

The platform D on which the bag is supported while being filled is adjustably mounted on the frame D¹ and carries the fixed base D² from which rises the lazytong structure D³ carrying the bag holding member D⁴. The springs D⁵ interposed between the base D² and the bag holding member D⁴, tend to raise the bag and extend the lazytong structure. The chain D⁶ limits the upward movement of the bag holding platform. 75

It will be evident that while I have shown in my drawings an operative device, still many changes might be made in size, shape and arrangement of parts without departing materially from the spirit of my invention and I wish therefore, that my drawings be regarded as in a sense diagrammatic. 80

The use and operation of my device are as follows: When it is desired to fill open mouthed bags with a machine such as mine, 85 which is particularly adapted to the filling of valve bags, I mount the two aprons upon the filling tube. The operator will then grip the two handles on the aprons bringing them together against the pressure of the spring until the catch drops down and holds them in the contracted position. The open mouthed bag will then be placed over the lower ends of the sprons coming up comparatively high upon them as indicated in 90 Fig. 2. The latch will then be released and the sprons will spread in response to the pressure of the spring, distending the mouth of the bag and holding it firmly upon the sprons. The machine will then be started 95 and feed material into the interior of the spron, whence it falls into the bag. As the bag fills its weight compresses the springs in the lazytong structure and causes the sides of the bag to tighten, thus drawing it down 100 upon the lower edge of the spron. When the bag is filled the operator will draw the two aprons back by grasping the two fixed 105

handles thereon, thus allowing the bag to slip off from the aprons and drop down so that its entire weight is supported at its base. In view of the fact that the springs at 5 the bottom are not made sufficiently strong to support the entire weight of the bag, the bag will drop down, giving room for the operator to tie it as indicated in Fig. 1. It will be observed that thus the bag is supported both at the top and bottom, the springs being so designed that a portion of the hood will be carried by the aprons and a portion by the springs at the bottom.

In the drawings I have shown my device 15 as applied to a machine specially adapted to filling valve bags, and I have used the term "filling tube." It will be understood, however, that my device need not be limited to a device practicable only for a valve bag filling machine, and the term "tube" need not in any sense be limited to a tube such as that adapted to enter and fill valve bags. It will be quite evident that this tube might be any kind of a tube, it might be inclined or 20 even vertical instead of horizontal, it might be a tube designed particularly for the filling of open mouth bags, it might take any desired or necessary form or position or be made of any suitable material, and my cap 25 or hood might be provided to conform to, but not in any sense depart from the spirit of my invention and claims.

I claim:

1. In a bag filling machine a filling tube 35 and a collapsible bag supporting hood mounted thereon, said hood being made up of two sections pivoted one upon the other and entirely closed at the top, and yielding means for forcing said pivoted sections 40 apart about their pivotal points to distend the mouth of the bag.

2. In a bag filling machine a horizontally disposed bag filling tube, means comprising a hood inclosing the discharge end of said 45 tube for completely closing the open mouth of a bag and means for supporting a bag upon said hood.

3. In a bag filling machine a hood made up of a pair of aprons always inclined one 50 to the other and pivoted together along one edge, a sleeve carried by one of said aprons and a bag filling tube upon which said sleeve is mounted.

4. In a bag filling machine a hood made 55 up of a pair of aprons always inclined one to the other and pivoted together along one edge, a sleeve carried by one of said aprons and a bag filling tube upon which said sleeve is mounted, each of said aprons having inwardly bent end members, the members of 60

one apron being in contact with and slidable upon the opposed members on the other.

5. In a bag filling machine a hood made up of a pair of aprons inclined one to the other and pivoted together along one edge, 65 a sleeve carried by one of said aprons and a bag filling tube upon which said sleeve is mounted, each of said aprons having inwardly bent end members, the members of one apron being in contact with and slidable 70 upon the opposed members on the other, said sleeve being mounted in one of said aprons, the opposed member being slotted to engage the sleeve.

6. In a bag filling machine a hood made 75 up of a pair of aprons inclined one to the other and pivoted together along one edge, a sleeve carried by one of said aprons and a bag filling tube upon which said sleeve is mounted, each of said aprons having inwardly bent end members, the members of one apron being in contact with and slidable 80 upon the opposed members on the other, handles fixed each upon one of the opposed pairs of sides and means for holding said 85 handles together.

7. In a bag filling machine a filling tube and an entirely closed bag supporting two part cap carried thereby, said two parts in pivotal engagement one with the other and 90 closed at their top.

8. In a bag filling machine a filling tube and a closed bag supporting two part cap carried thereby, said two parts in pivotal engagement one with the other near their 95 upper ends, yielding means resisting the approach of said parts one to the other at their lower edges.

9. In a bag filling machine a filling tube and a closed bag supporting two part cap 100 carried thereby, said two parts in pivotal engagement one with the other near their upper ends, yielding means resisting the approach of said parts one to the other at 105 their lower edges, and means for locking said parts together.

10. In a bag filling machine comprising a horizontally disposed filling tube, a two part A-shaped hood mounted thereon, the two parts of said hood being pivoted one upon 110 the other, said hood being open at the bottom and having means about said open bottom for engaging the open end of the bag yielding means for pressing the two pivoted hood parts outwardly to distend the bag.
